UNITED STATES PATENT OFFICE.

GEORGE EVANS, OF LYON, MISSISSIPPI.

WAGON END-GATE.

SPECIFICATION forming part of Letters Patent No. 445,167, dated January 27, 1891.

Application filed October 17, 1890. Serial No. 368,500. (No model.)

To all whom it may concern:

Be it known that I, GEORGE EVANS, a citizen of the United States of America, residing at Lyon, in the county of Coahoma and State of 5 Mississippi, have invented certain new and useful Improvements in Tail - Gates for Wagon-Bodies; and I do hereby declare the following to be a full, clear, and exact description of the invention, such as will enable others skilled in the art to which it appertains to make and use the same.

My invention relates to certain novel and valuable improvements in end-gates or tail-boards for wagons, which improvements will 15 be fully understood from the following description and claim, taken in connection with the annexed drawings, in which—

Figure 1 is a perspective view in detail of my improvement applied to part of a wagon- 20 body. Fig. 2 is a perspective view of the tail-board and its hooked tie-rod attached. Figs. 3 and 4 are sectional details.

Similar letters of reference indicate corresponding parts in the several figures.

Before describing particularly my invention I admit that it is old and well known in tail-gates for wagons to use a tie or brace-bar for binding the sides of the wagon-body and holding the same solidly against the tail- 25 board. My main object is to attach permanently yet movably the tie-bar to the tail-board, so that the former will not be liable to loss or displacement.

Referring to the annexed drawings by letters, A A designate the sides of a wagon- 30 body, and B the floor or bottom thereof, which body may be constructed and mounted in the usual well-known manner.

C designates the tail-board or end-gate, 35 which is provided posteriorly with battens or vertical braces D D. This tail-board is also provided with a horizontal tie brace-rod G, having hooks b b at its ends turned upward- ly. This rod G passes freely and has end 40 play through the braces D D, and at the mid-

dle of its length it is squared, as indicated at d, and passes through a square recess made through a staple d' driven into the board C. The termini of the square portion d afford shoulders c'. The brace-rod thus applied is 50 free to be adjusted endwise, limited by the said shoulders. The rod is thus permanently but movably applied to the tail-board.

E and F designate inside facing-boards, secured rigidly to the inner sides of the side- 55 boards of the wagon-body, forming vertical grooves a a, adapted to receive the tail-board, as shown in Fig. 1.

On one side of the body is rigidly fixed a staple f, and on the opposite side is applied 60 a movable staple g, adjustable by a nut h. Both staples are provided with links, the staple f with a link e and the staple g with link e', as shown in Figs. 1, 3, and 4.

When the tail-board is put in its place, as 65 indicated in Fig. 1, and the links e e' are engaged with the hooks b b' on the endwise-movable rod G, the nut h is screwed up and the parts are rigidly held and braced.

Having described my invention, what I 70 claim as new, and desire to secure by Letters Patent, is—

The combination of the body, the fixed and adjustable staples secured to the rear ends of the sides thereof, and the links connected to 75 said staples, with the tail-gate, the longitudinally-movable horizontal rod attached to the gate and having its central portion squared and shouldered and passed through a staple attached to the gate by which the movement 80 of the rod is regulated, and having its ends formed into upturned hooks adapted to be engaged by the links, all substantially as set forth.

In testimony whereof I affix my signature in 85 presence of two witnesses.

GEORGE EVANS.
